DESIGN FOR A LOUNGING PAJAMA

Elias Sayour, Brooklyn, N. Y.

Application April 20, 1937, Serial No. 68,879

Term of patent 3½ years

To all whom it may concern:

Be it known that I, Elias Sayour, a citizen of the United States and a resident of the city of New York (Borough of Brooklyn), in the county of Kings and State of New York, have invented a new, original, and ornamental Design for a Lounging Pajama, of which the following is a specification, reference being had to the accompanying drawing, forming part thereof.

Figure 1 is a front perspective view of a lounging pajama showing my new design;

Figure 2 is a rear perspective view of the pajama shown in Figure 1;

Figure 3 is an enlarged fragmentary view illustrating the contrasting coloring of the panel and associated parts.

The essential features of my design reside in the one-piece pajama having a contrastingly colored panel extending from the neck to the relatively high waistline and which contrast is repeated on the collar, cuffs, and sash, as shown.

I claim:

The ornamental design for a lounging pajama, substantially as shown and described.

ELIAS SAYOUR.
